UNITED STATES PATENT OFFICE.

JAMES F. PLACE, OF MONTCLAIR, NEW JERSEY, ASSIGNOR TO CHARLES S. UPTON, OF NEW YORK, N. Y.

OIL STOVE AND LAMP.

SPECIFICATION forming part of Letters Patent No. 520,499, dated May 29, 1894.

Application filed August 17, 1893. Serial No. 483,361. (No model.)

To all whom it may concern:

Be it known that I, JAMES F. PLACE, a citizen of the United States, residing in Montclair, Essex county, New Jersey, have invented 5 certain new and useful Improvements in Oil Stoves and Lamps, of which the following is a specification.

This invention relates to the class of stoves and lamps which employ oil as a fuel, and the 10 object is to provide a construction wherein the heating attachments are borne by the lamp reservoir, all as will be hereinafter described.

In the accompanying drawings, serving to 15 illustrate my invention—Figure 1 is a side view of an oil-stove embodying my improvements, the lamp being in elevation and the heating attachment on line 1, 1, in Fig. 2. Figs. 1^a and 1^b are details of the construction 20 which will be hereinafter described. Fig. 2 is a plan of the stove.

A is the oil-reservoir, B a central-draft burner, and C a flame-spreader on the burner. These may be of the usual construction, and 25 they are capable of being used with a glass chimney, for purposes of illumination, as any ordinary lamp.

The heating, or stove attachment comprises 30 a special chimney, a platform which rests on and is clamped to the chimney, and legs to support the platform and chimney, the entire heating attachment being supported by the legs, on the oil-reservoir A. In Fig. 1 the entire heating attachment is represented in vertical mid-section. The chimney is in two superposed sections; the lower section, D, which 35 will usually be of cast metal, is flared upwardly and extends up to the combustion point about the level of, or just above the 40 level of the top of the flame-spreader. The contracted base of the chimney section D takes within the raised flange on the chimney gallery b, usually occupied by the glass chimney of an ordinary lamp. This section D of 45 the chimney has on it laterally projecting branches, d, there being four of these branches as herein shown. The upper section, D', of the chimney will be, by preference, of sheet metal and cylindrical. At its lower end this

section rests on and is supported by the lower 50 chimney-section D, and at its upper end it takes under and supports the platform E. The platform and chimney are clamped together by four straining rods, e, which connect the platform with the respective branches 55 d, screw-threads on the rods being employed to effect the clamping. Legs, e^x, on the heating attachment support it on the reservoir A, thus taking the weight of the attachment off from the chimney-gallery and affording also 60 a broader area of support at the base than would be afforded by the gallery. As herein shown the rod e and leg e^x, are integral, being made from a piece of stout wire. The rod is screw-threaded at its upper end, e', and 65 adapted to screw into a nut e³, above the platform, and at the point where it passes through a hole or aperture in the branch d, it is bent into the form of a crank, the portion e², at the bend, taking under the branch and engaging 70 a shallow groove, d', in the under side thereof. This construction is clearly shown in Figs. 1^a and 1^b, the former being an end elevation of a branch d, and the latter a plan thereof.

In assembling the parts the rod e is passed 75 upwardly through the aperture in the branch d and its upper screw-threaded end screwed into the nut e³, by rotating the rod, the leg e^x serving as a crank for the purpose. When the rod has been screwed in nearly home, the 80 portion e² of the same will finally wipe into the groove d' along the under side of the branch by reason of the springing of the parts. The nuts e³, screwed onto the upper extremities of the rods e, may rest in recesses 85 in the platform. The length of the legs e^x will be such that the base of the chimney will enter into the flanged chimney-gallery but not bear heavily thereon.

The heating attachment may be lifted off 90 from the lamp and replaced at will.

In a common form of lamp the oil-reservoir rests in an ornamental outer shell or casing. When such a lamp is employed the heating attachment may be supported on this outer 95 casing.

Having thus described my invention, I claim—

In an oil-stove, the combination with the platform E, the upper section of the chimney and the lower section, D, of the chimney provided with laterally projecting, apertured branches d, each having a groove d' in its lower face, of the screw-threaded rods e, secured to the platform at their upper ends by screws and extending through the apertures in the respective arms d, and each having a bent portion e² which engages the groove in

the branch and a leg portion e³, substantially as set forth.

In witness whereof I have hereunto signed my name in the presence of two subscribing witnesses.
